BOTTLE

Stanley K. Johns, Toronto, Ontario, Canada, assignor to
St. Lawrence Manufacturing Company, Inc., Giffard,
Quebec, Canada, a corporation of Quebec

Filed Aug. 16, 1963, Ser. No. 76,231

Term of patent 7 years

(Cl. D58—8)

FIG. 1 is a front elevation of a bottle embodying my new design;

FIG. 2 is a top plan view thereof;

FIG. 3 is a bottom plan view thereof;

FIG. 4 is a cross section taken along lines 4—4 of FIG. 1; and,

FIG. 5 is a fragmentary cross section taken along line 5—5 of FIG. 1.

I claim:

The ornamental design for a bottle, as shown.
